UNITED STATES PATENT OFFICE.

WASHINGTON I. TUTTLE, OF BALTIMORE, MARYLAND, ASSIGNOR TO TIN DECORATING COMPANY OF BALTIMORE, OF BALTIMORE, MARYLAND, A CORPORATION OF NEW JERSEY.

SUPPLEMENTAL COVER FOR BOXES.

1,153,276.

Specification of Letters Patent. Patented Sept. 14, 1915.

Application filed October 3, 1913. Serial No. 793,179.

To all whom it may concern:

Be it known that I, WASHINGTON I. TUTTLE, a citizen of the United States, residing at Baltimore, State of Maryland, have 5 invented new and useful Improvements in Supplemental Covers for Boxes, of which the following is a specification.

My present invention relates to certain new and useful improvements in removable 10 supplemental transparent covers for boxes, as for instance boxes containing merchandise sold from the original package, such as cigars and other forms of tobacco, candies, cakes, fruits, etc., wherein it is desirable to 15 display the contents of the box but at the same time protect the same from atmospheric impurities.

One object of the invention is to provide 20 a supplemental cover made up of standard units that may be assembled as desired to form a cover of the proper size to fit any box, thus greatly reducing the cost of manufacture of the covers and making it possible 25 to fill orders more promptly, as one set of dies will be sufficient for a variety of sizes of covers, and the cover units may be manufactured in quantities and stored away for assembly into covers when desired.

Another object of the invention is to provide 30 a supplemental cover of the type referred to wherein no special hinge for the same is required, the cover being provided with rigid means for attachment to the ordinary hinged lid of the box to which the supplemental cover is applied, and the said hinge for the box-lid serving also as the hinge for the supplemental cover.

A still further object of the invention is 35 to provide a supplemental cover of the character referred to wherein the means for attaching the same to the hinged lid of the box serves also to maintain the said lid in open position while the supplemental cover is closed, opening of the said supplemental cover being accomplished by downward and 40 backward pressure exerted upon the hinged lid of the box; or in other words, opening movement of the supplemental cover is accomplished by moving the hinged lid.

50 The invention has in view other more or less important objects all of which will be made clear in the following detail description thereof, taken in connection with the

accompanying drawings, which are illustrative of one embodiment of the invention, 55 and wherein—

Figure 1 is a perspective view of a box having associated therewith a supplemental cover made according to the present invention. Fig. 2 is a transverse vertical sectional view taken on the line 2—2 of Fig. 1. Fig. 3, is a detail perspective view of one of the inner corner units of the cover-frame showing the means for attaching the same to the hinged lid of the box. Fig. 4, is a bottom perspective of the same. Fig. 5, is a plan view of the blank from which the said corner section is made. Fig. 6, is a detail perspective view of one of the outer corner units of the cover-frame. Fig. 7, is a bottom perspective of the same. Fig. 8, is a plan view of the blank from which the said outer corner unit is formed. Fig. 9, is a top plan view of the supplemental cover complete. Fig. 10, is a bottom plan view of the 75 same.

The supplemental cover as shown consists of a frame made up of sheet metal units, 80 extensibly connected, in order that frames of different sizes may be constructed from said units to fit boxes of different sizes, the said frame carrying a transparent panel and provided also with means for removably attaching the frame to the hinged lid of the box, whereby rearward and downward movement of the lid will cause the supplemental cover to be raised. The said frame comprises a pair of rear corner units 10, of 85 right angular formation, each unit having an upwardly and rearwardly extending lid-engaging and supporting member 12, arranged at an obtuse angle thereto and formed integrally rigid therewith, said members 12, each provided with an inwardly 90 extending flange 13, designed to embrace an edge of the lid 14, of the box 15 as shown. The forwardly extending portion 10^a of each rear corner unit 10 is provided with a downwardly extending side flange 16, having an 95 upstanding portion 17, lying parallel with, but spaced from the flange 16, to provide a way for an interconnecting end spacer strip 18, of right angle formation that has a sliding or telescoping connection with the said corner unit (and each unit is also provided 100 with a lateral lip 19, to support the glass

panel 20, of the supplemental cover. The laterally extending portion 10^b of each rear corner unit is provided with an overturned flange or lip 21, overlying the upper face thereof, and with which a tongue 22, at the end of a rear spacer strip 23, may have a telescopic connection. The rear spacer strip 23, has a plate 24, formed integral therewith and extending upwardly at an obtuse angle therefrom, said plate 24, being provided at its opposite longitudinal edges with overturned flanges 25, 26, with which the upwardly and rearwardly extending lid-engaging members 12, of the rear corner units 5 may have telescopic connection, whereby the said corner units may be brought closer together or moved farther apart, while at the same time maintaining telescopic connection with the rear frame spacer to accommodate 10 the frame to boxes of different length. The said laterally extending portion 10^b of each rear corner unit is also provided with a downwardly extending lip 21^a struck therefrom, which lips constitute stops or abutments to engage an edge of and hold the 15 transparent panel 20 within the frame.

The front corner units 27, of the frame of which there are two in number, are of right angle formation and each member thereof 20 has a downwardly extending flange 28, provided with an upturned portion 29, which upturned portion 29, constitute ways for the end spacer strips 18, and the front spacer strip 30, each of which strips is of angular 30 formation, or L shaped in cross-section, and each of which has a telescopic connection at its opposite ends with the corner units. The front corner units 27, like the rear corner units are also provided with lateral lips 31, 35 that serve as supports to retain the glass panel 20, within the frame.

From the foregoing description taken in connection with the accompanying drawing, it will be seen that the frame comprises front 40 and rear corner units and side and end spacer strips having telescopic connections with said corner units, and that said corner units may be adjusted toward and from each other to provide corner-frames of different sizes. It will also be seen that no specially provided hinge is necessary with my improved construction of cover, as the cover frame is provided with means for removably attaching the same directly to the hinged lid of the box in such a manner that the lid-hinge serves also as the hinge for the supplemental cover, and at the same time the said cover-engaging or attaching means 45 serves to maintain the box-lid in open position and also constitutes a means for lifting the supplemental cover by simply forcing the open box-lid rearwardly and downwardly about the hinge.

By making the frame of sheet metal corner and spacer units of standard sizes, these

units may be manufactured in quantity from small pieces of scrap metal and assembled into cover frames of different sizes to suit any given box, within certain limits. This greatly simplifies and reduces the cost of manufacture, since only one set of corner-units is necessary, inasmuch as the frame corner-units are adjustable toward and from each other, or in other words, are laterally and longitudinally adjustable or extensible.

If desired the frame units, when assembled, may be permanently secured together by making punch indentations 32, in the overlapping portions of the corner and spacer units as more clearly shown in Fig. 3, or the parts may be soldered together, but I prefer the punch indentations as this is a simpler and cheaper method.

Obviously my improved lid-engaging and supporting means may be employed in connection with other than extensible corner frames without departing from the spirit of the invention.

What I claim is:

1. The combination with a box and hinged lid, of a supplemental cover for a box, said cover having longitudinally extensible lid-engaging and supporting means carried thereby adapted to maintain the cover in open position and serve also to lift the cover upon swinging movement of the lid on its hinge.

2. A supplemental cover for a box comprising an extensible frame, embodying corner-units and intermediate spacer-strips, adjustably connecting said units, two of said corner-units having means forming a slot therefor for attaching the cover to the lid of the box.

3. A supplemental cover for a box comprising an extensible frame, embodying corner-units and intermediate spacer-strips, adjustably connecting said units, each of said corner-units being provided with an upwardly and rearwardly inclined lid-engaging and supporting member integral therewith, and one of said spacer-strips having a plate formed integral therewith that extends across the front of the box-lid adjacent its hinge.

4. A supplemental cover for a box comprising an extensible frame, embodying front and rear corner-units, and front and side spacer-strips, adjustably connecting said corner-units, each of said rear corner-units being provided with an upwardly extending member having means for closing an end of a hinged box-lid.

5. A supplemental cover for a box comprising an extensible frame, embodying front and rear corner-units, and front and side spacer-strips, adjustably connecting said corner-units, and each of the corner-units being provided with an upwardly extending member having an inwardly

turned lip to embrace an end of a hinged box-lid.

6. A corner unit for a cover frame, comprising a plate having portions arranged at right angles to each other and in the same horizontal plane, each corner unit having means for engaging the face of a transparent cover plate in the angle between said right angle portions and one of said portions having a rigid, integrally formed member provided with means for engaging and supporting a box-lid.

7. A corner unit for a cover frame, comprising a plate having portions arranged at right angles to each other and in the same horizontal plane, each corner unit having means for engaging the face of a transparent cover plate located in the angle between said right angle portions and one of said portions having a rigid, integrally formed upwardly and backwardly inclined member provided with a rearwardly ex-

tending lip to receive and support a hinged box-lid.

8. A corner unit for a cover frame, comprising a plate having portions arranged at right angles to each other and in the same horizontal plane, each corner unit having means for engaging the face of a transparent cover plate in the angle between said right angle portions, and one of said portions having a rigid, integrally formed upwardly inclined member provided with means to engage a box-lid, and the said portion also provided with a lip lying substantially parallel with the face thereof to receive the end of a spacer strip.

In testimony whereof I have hereunto set my hand in presence of two subscribing witnesses.
